(57) **CLAIM**

We claim the ornamental design for a tire, as shown and described.

DESCRIPTION

FIG. 1 is a perspective view of a tire showing our new design;

FIG. 2 is an enlarged fragmentary perspective view of the tire as shown in FIG. 1;

FIG. 3 is a front view of the tire as shown in FIG. 1;

FIG. 4 is an enlarged fragmentary front view of the tire as shown in FIG. 1;

FIG. 5 is a back view of the tire as shown in FIG. 1;

FIG. 6 is a left side view of the tire as shown in FIG. 1;

FIG. 7 is a right side view of the tire as shown in FIG. 1;

FIG. 8 is a Bottom view of the tire as shown in FIG. 1; and,

FIG. 9 is a Top view of the tire as shown in FIG. 1.

In the drawings, the broken lines depict environmental subject matter only and form no part of the claimed design.
